Primary Examiner—Alan P. Douglas*Assistant Examiner*—M. N. Pandozzi*Attorney, Agent, or Firm*—Cushman, Darby & Cushman**[57] CLAIM**

The ornamental design for decalcomania for china dinnerware, as shown and described.

DESCRIPTION

FIG. 1 is a plan view of my new design for decalcomania for china dinnerware. The decalcomania has no substantial thickness and the fragmentary broken line shows environmental structure only and forms no portion of the design.
